Frank C. Fischer
ATTORNEYS

UNITED STATES PATENT OFFICE.

FRANZ A. FULLER, OF NEWARK, NEW JERSEY.

SAFETY RAZOR.

Application filed January 10, 1920. Serial No. 350,488.

To all whom it may concern:

Be it known that I, FRANZ A. FULLER, a citizen of the United States, residing in the city of Newark, in the county of Essex and State of New Jersey, have invented certain new and useful Improvements in Safety Razors, of which the following is a full, clear, and exact description, such as will enable others skilled in the art to which it pertains to make, construct, and use the same, reference being had to the accompanying drawings, and to numerals of reference marked thereon, forming a part of this specification.

This invention relates to improvements in safety razors, and more particularly to such as are adapted especially for stropping the safety razor blades. My invention has for its object, the production of a safety razor having a frame adapted to slide longitudinally of a strop, a blade holder being pivotally supported in said frame and means for rocking the blade while in the frame, for stropping the edges thereof. Another object of my invention is to provide means to cause a strop to rock a pivotally supported blade holder with its pivotally supported blade in such a manner as to prevent the blade from cutting or injuring the strop, and also having means for positively adjusting the blade relative to the guard teeth. With this end in view, my invention consists in certain novelties of construction and arrangement of parts as hereinafter set forth and pointed out in the claims. While the preferred forms of my invention are illustrated in the accompanying drawings, yet it is to be understood that minor detail changes may be made without departing from the scope thereof.

In the drawings,

Figure 1 represents, a side elevation in section, illustrating the manner in which the device is to be used for stropping the blade, and illustrating the cutting edge of the blade, both in full and in dotted lines in stropping relation to the strop.

Figure 2 represents, a rear elevation of my improved device.

Figure 3 represents, on an enlarged scale a fragmentary sectional elevation illustrating the manner in which the pivotally-supported blade holder support is pivotally secured to the body or frame of my device.

Figure 4 represents, a side elevation of my improved device, illustrating the pivotally-

supported blade holder support which carries the blade holder in shaving relation to the frame.

Figure 5 represents, on an enlarged scale 60 a plan view of the blade holder and blade; and

Figure 6 represents, a sectional view of the same taken on line α — α looking in the direction indicated by the arrow. 65

Similar numerals of reference refer to like parts throughout the specification and drawings.

In the drawings, 1 represents the body or frame of my improved device, which body or 70 frame may be stamped from sheet metal or the like, and afterwards bent into the desired shape as shown.

Said body or frame comprises preferably a curved body portion extending centrally 75 and lengthwise of the frame, the two opposite ends of the frame being provided with two downwardly extending lugs or ears 2 and 3 parallel each to each.

The frame 1 is constructed to grip the 80 blade at the front corners, the sharpened edge of the blade resting upon the bent-over end of the guard 4, which is provided with the usual perforations 5, the free end of which is bent downwardly, and which is 85 sufficiently in advance of the edge of the blade to afford the necessary protection against accidental cutting.

The forward and outer end of the guard 4 has upwardly extending stops 6 for engagement with the corners of the cutting edge of the blade, to prevent said cutting edge from projecting too far beyond the guard 4, to at all times maintain the cutting edge of the razor in the proper and adjusted 95 position relative to the guard teeth.

These stops 6 may, for convenient sake, be formed integral with the frame 1, or secured thereto in any convenient or desired manner.

The rear edge of the body or frame 1 is preferably bent downwardly, and to the end of which is secured a removable handle 7 which, if desired for convenience in packing, may be detached from the frame. 105

The pivotally-supported blade holder support comprises two opposite side portions 8 and 9, parallel each to each, and connected at its lower end by means of a cylindrical rod 10, preferably located on the 110 underside of the body or frame 1, the ends of which pass through the apertured ears or

lugs 2 and 3 and riveted to the side portions 8 and 9 as clearly indicated in the drawings, see Figure 3 of the drawings.

Journalled in the side portions 8 and 9

5 of the blade holder support intermediate of its end is a roller 11 to be engaged by the strop when the device is used for stropping the blade as illustrated in Figure 1 of the drawings.

10 Also journalled in the side portions 8 and 9 of the blade holder support is a cylindrical rod or shaft 12 which carries the blade holder 13, which holder may consist of a piece of sheet metal wrapped around said rod or shaft 12, and secured thereto in any convenient or desired manner, so as to provide resilient clamping jaws 14 and 14 to receive the razor blade 15 between themselves, as has been common in general 15 heretofore.

20 The side portions 8 and 9 have upper and lower holes forming bearings for the ends of the cylindrical rod or shaft 12 and the roller 11, both extending transversely 25 of the blade holder.

25 The rod or shaft 12 and the roller 11 are connected by means of pinions or gears 16 and 16, so that by drawing the device along the strop will tend to turn the upper 30 rod or shaft 12 carrying the blade holder 13, and when the direction of sliding the device is reversed the said upper rod or shaft 12 will be turned according to the principles already well understood in the art.

35 The plane portion of the blade is provided with a central aperture 17 conveniently located therein, adapted to engage with a roller 18 conveniently carried on one 40 of the clamping jaws 14 of the blade holder 13, to firmly secure and prevent the accidental displacement of the blade from said holder.

45 The razor blade, as shown, is preferably made from sheet metal provided with a longitudinal cutting edge, but I wish it to be understood that razor blades of peculiar construction may be employed.

50 Pivots secured in the aligned bearings 19 formed integral with the body or frame 1 is the latch plate 20 preferably made from a single piece of suitable material, the ends of which are bent around to engage with said bearings.

55 The central portion of said latch plate 55 is provided on its inner side with an engaging element 21 designed to bear upon the rear face of the roller 11, in order that when said latch plate is manipulated by means of the finger piece 22 formed on the 60 latch plate, the cutting edge of the blade 15 is brought into an adjusted operative position relative to the guard.

65 The two opposite ends of the frame 1 are recessed so as to provide stops 24 formed on the ends of said frame so that the move-

ment of the two opposite side portions 8 and 9 of the pivotally-supported blade holder support is limited in its forward movement.

70 The rearward movement of said pivotally-supported blade holder support is limited by the roller 11 engaging with the rear end of the frame 1 in which the aligned bearings for the pivoted latch plate are secured.

75 The movement of the pivotally supported blade holder support is only limited in its forward and rearward direction as just described when the razor blade is released from the guard of the frame for cleaning 80 the same.

85 During the stropping operation the forward and rearward movement of the pivotally-supported blade holder support is limited by the strop.

90 The operation of the device is as follows: a safety razor blade is inserted between the resilient clamping jaws 14—14 of the blade holder 13; the strop 23 is then passed over the body or frame 1, through the pivotally-supported blade holder support and under the roller 11 on said blade holder support, and then out through the other end of the frame 1 of the device as clearly indicated in Figure 1 of the drawings.

95

95 The attaching end of the strop (not shown) is hooked over any suitable support while its opposite end (likewise not shown) is held in one hand. The other hand grips the handle 7 of the device, and reciprocates 100 said device back and forth along the strop, thereby permitting the edge of the blade to be engaged with the strop.

100

105 The present invention provides a very efficient and exceedingly simple and inexpensive device, the same being constructed of a minimum number of parts, which are of such a shape as to lend themselves ready to manufacture by the use of suitable punches and dies from ordinary sheet metal, and 110 which parts are reduced to the simplest operative efficiency; and further, the invention provides a safety razor in which the accidental cutting or injuring of the strop by the blade is prevented.

115

110 Experience has demonstrated that the organization above described is a highly efficient one, and while I have shown the preferred embodiment of my present invention, I do not wish to be limited to the exact details of construction shown and described, as obvious modifications thereof, not involving the exercise of invention, may be made by any skilled mechanic, and such departures from what is herein set forth, 125 I consider within the scope and terms of my claims.

120

125 I claim:

1. A safety razor comprising a frame, having guard teeth at one edge, adapted to 130

- slide longitudinally of a strop, a handle extending from the frame, a blade holder support pivotally connected to the under side of said frame, a roller in said blade holder support located above the frame, a blade holder pivotally connected to said blade holder support above said roller, means carried by said blade holder support for transmitting rotary movement to said blade holder from said roller thereby permitting both surfaces of the cutting edge of the blade to be engaged with the strop and pivotal means located on the frame for adjusting the blade relative to the frame.
- 15 2. A safety razor comprising a frame, having guard teeth at one edge, adapted to slide longitudinally of a strop, a handle extending from the frame, a blade holder support comprising opposite side portions connected by a lower cross piece pivotally connected to and extending entirely across the under side of said frame, a roller in said blade holder support located above the frame, a blade holder pivotally connected to said blade holder support above said roller, means carried by said blade holder support for transmitting rotary movement to said blade holder from said roller, and means pivotally secured to the frame adapted to engage with said roller located in the blade holder support for adjusting the blade relative to the frame.
- 20 3. A safety razor comprising a frame, having guard teeth at one edge, adapted to slide longitudinally of a strop, a handle extending from the frame, a blade holder support comprising opposite side portions connected by a lower cross piece pivotally connected to and extending entirely across the under side of said frame, a roller in said blade holder support located above the frame, a blade holder pivotally connected to said blade holder support above said roller, a blade located in said blade holder, means carried by said blade holder support for transmitting rotary movement to said blade holder from said roller thereby permitting both surfaces of the cutting edge of the blade to be engaged with the strop and a latch, the ends of which are pivotally located in the aligned bearings of the frame for adjusting the blade relative to the frame.
- 25 4. A safety razor comprising a frame provided with aligned bearings at its ends adapted to slide longitudinally of a strop, a handle extending from the frame, a blade holder support comprising opposite side portions connected by a lower cross piece pivotally connected to the under side of said frame, a roller in said blade holder support located above the frame, a blade holder pivotally connected to said blade holder support above said roller, a blade located in said blade holder, means carried by said blade holder support for transmitting rotary movement to said blade holder from said roller thereby permitting both surfaces of the cutting edge of the blade to be engaged with the strop and a latch, the ends of which are pivotally located in the aligned bearings of the frame for adjusting the blade relative to the frame.
- 30 5. A safety razor comprising a frame, having guard teeth at one edge, adapted to slide longitudinally of a strop, a handle extending from the frame, a blade holder support comprising opposite side portions connected by a lower cross piece pivotally connected to and extending entirely across the under side of said frame, a roller in said blade holder support located above the frame, a blade holder pivotally connected to said blade holder support above said roller, a blade located in said blade holder, means carried by said blade holder support for transmitting rotary movement to said blade holder from said roller thereby permitting both surfaces of the cutting edge of the blade to be engaged with the strop and a latch, the ends of which are pivotally located in the aligned bearings of the frame for adjusting the blade relative to the frame.
- 35 6. A safety razor comprising a frame, having guard teeth at one edge, adapted to slide longitudinally of a strop, a handle extending from the frame, a blade holder support comprising opposite side portions connected by a lower cross piece pivotally connected to and extending entirely across the under side of said frame, a roller in said blade holder support located above the frame, a blade holder pivotally connected to said blade holder support above said roller, a blade located in said blade holder, means carried by said blade holder support for transmitting rotary movement to said blade holder from said roller thereby permitting both surfaces of the cutting edge of the blade to be engaged with the strop and a latch, the ends of which are pivotally located in the aligned bearings of the frame for adjusting the blade relative to the frame.
- 40 7. A safety razor comprising a frame, having guard teeth at one edge, adapted to slide longitudinally of a strop, a handle extending from the frame, a blade holder support comprising opposite side portions connected by a lower cross piece pivotally connected to and extending entirely across the under side of said frame, a roller in said blade holder support located above the frame, a blade holder pivotally connected to said blade holder support above said roller, a blade located in said blade holder, means carried by said blade holder support for transmitting rotary movement to said blade holder from said roller thereby permitting both surfaces of the cutting edge of the blade to be engaged with the strop and a latch, the ends of which are pivotally located in the aligned bearings of the frame for adjusting the blade relative to the frame.

This specification signed and witnessed this 26th day of August 1919.
